UNITED STATES PATENT OFFICE.

JOHN PETERSON, OF NEW YORK, N. Y.

RUNAWAY-STOP.

1,019,699.

Specification of Letters Patent.

Patented Mar. 5, 1912.

Application filed September 20, 1911. Serial No. 650,410.

To all whom it may concern:

Be it known that I, JOHN PETERSON, a citizen of the United States, and a resident of the city of New York, borough of Brooklyn, 5 in the county of Kings and State of New York, have invented a new and Improved Runaway-Stop, of which the following is a full, clear, and exact description.

This invention relates to runaway stops, 10 and has reference more particularly to apparatus for halting runaway horse-propelled or other vehicles, and is employed in combination with a bridge or other roadway, comprising a normally inoperative, movable 15 member adapted when projected into an operative position to be engaged by a vehicle traveling along the roadway, and means for controlling the movement of the member.

The object of the invention is to provide 20 simple, strong and efficient apparatus for bringing to a stop runaway vehicles of different types, with a minimum of damage to the vehicle, and with certainty and rapidity, which can be employed with the roadways 25 of bridge or other structures, or at other localities where its use is advisable, and which can be controlled and manipulated simply and rapidly from distant points.

The invention consists in the construction 30 and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a side elevation of a portion of a bridge roadway showing an embodiment 40 of my invention applied thereto; Fig. 2 is a similar view showing certain of the parts in different positions; Fig. 3 is a longitudinal section of the bridge roadway; Fig. 4 is a transverse section of the roadway, on the 45 line 4—4 of Fig. 3; Fig. 5 is a similar view on the line 5—5 of Fig. 3; Fig. 6 is also a transverse section on the line 6—6 of Fig. 1; Fig. 7 is an enlarged section on the line 7—7 of Fig. 2; Fig. 8 is a horizontal section on 50 the line 8—8 of Fig. 7; and Fig. 9 is a longitudinal section on the line 9—9 of Fig. 7.

Before proceeding to a more detailed explanation of my invention it should be clearly understood that while I have illustrated 55 the apparatus as applied to a bridge

roadway, and notwithstanding that it is particularly advantageous as used with the same, it can also be employed for like purposes in connection with other roadways or structures along which different vehicles 60 travel. It will be understood that a runaway horse-propelled or other vehicle is liable to cause material damage upon a roadway such as that of a bridge, which is frequently narrow and crowded.

My invention provides means for surely and expeditiously bringing runaway vehicles to a halt, without injury to the vehicles, thereby also obviating the danger of damage to other vehicles.

Referring more particularly to the drawings I have shown for example, a bridge roadway 10, consisting of suitable planking or the like carried upon stringers or beams 11, and having at the sides uprights 12 upon 75 which are carried side rails 13. It will be understood that the structural details of the bridge form no part of my invention and that the stringers 11 may be I-beams, the posts 12 of hollow, angular cross-section, and 80 the rails 13 also I-beams. At one or more suitable points along the length of the roadway, the rails 13 of the bridge are interrupted to form gaps 14 in which are located

70 rail sections 15 somewhat shorter than the gaps, and each pivotally connected with a corresponding end of a rail 13 by means of a suitable hinge 16. Leaf or other springs 85 secured to adjacent uprights 12 engage the rail sections 15 and tend normally to 90 raise them into alignment with the rails 13. The rail sections are held in the normally inclined positions shown in Figs. 1 and 3, by means of catches 18 engaging keeper extensions 19 of the rail sections and mounted at 95 the ends of transverse shafts 20 journaled in bearings 21 of the outer stringers. It will be seen that when the catches are released by suitable means which will be described hereinafter, the rail sections 15 swing upward under the influence of the springs 17, for a purpose which will appear below.

For the sake of brevity I will describe but a single apparatus, notwithstanding that one or more may be applied along the 105 length of the roadway at suitable points thereof. Adjacent to the shaft 20 I provide a second transverse shaft 22, likewise journaled in bearings 23 of the outer stringers, and having secured rigidly thereto at one 110

end, a double lever 24, the arms of which are connected with operating lines 25 extending in different directions to suitable points of the roadway at which are stationed 5 operatives for the purpose. These operatives are preferably bridge attendants whose locations permit them a clear view of the roadway so that they will readily see any approaching runaway vehicle. The roadway 10 at the apparatus is provided with a transverse groove or recess 26 in which is located a rod 27 mounted at the ends of arms 28 rigidly secured to the shaft 22. The rod 27 constitutes a normally inoperative 15 releasing member which does not interfere with the bridge traffic when it is placed in its normal position in the recess 26. A similar, parallel recess 29 extends across the roadway under the rail sections 15, as does 20 the recess 26. Located within the recess 29 is a length of chain 30, the ends of which are secured in any convenient manner to travelers 31 normally positioned upon the rail sections 15. The member 30 constitutes a 25 normally inoperative barrier adapted to be engaged by the vehicle when it is projected into an operative position. A line 32 or other suitable connection joins one of the arms 28 and one of the catches 18 so that 30 after the shaft 22 has been operated to project the rod 27 a further movement of the shaft 22 will release the catches 18.

Each of the travelers 31 comprises an elongated, channel-shaped body having at 35 the lower edges in-turned flanges 33. The travelers are movably mounted upon the rail sections and are likewise designed to travel along the rails 13 with the flanges 33 engaging underneath the upper flanges of the 40 rails. Within each traveler, at the sides thereof, are located vertical rollers 34 mounted upon suitable spindles 35 and engaging at the flange edges of the rails. Similar transverse rollers 36 mounted upon spindles 37 45 are provided within the travelers, and engage at the faces of the upper rail flanges. The travelers are thus mounted to move with a minimum of friction. I prefer to secure the chain 30 to the travelers by means of 50 lugs 38 extending from the inner faces of the travelers and provided with openings to receive the end links of the chain. Each traveler furthermore, at the rear end has a lug 39 provided with an opening to receive 55 the end link of a chain 40. These chains 40 pass over channel-shaped saddles 41 having downwardly disposed, rounded ends and each arranged upon one of the adjacent uprights 12. The uprights have substantially 60 vertical offset arms 42 secured thereto and provided with lugs in which are pivotally mounted brake levers 43 each having a brake shoe 44. Chains or other flexible members 45 are fastened at the ends of the brake arms 65 40, and are partly wound upon brake drums

46 carried at the ends of a transverse shaft 47 journaled in bearings 48 at the lower ends of the uprights. The shaft furthermore, has a central brake drum 49 upon which is partly wound a chain 50 or other flexible 70 member, permitting the shaft to be actuated from a convenient controlling station, by one of the operatives.

The operation of my invention is as follows: As soon as one of the bridge attendants perceives a runaway vehicle approaching the apparatus, he employs one or the other of the controlling lines 25, to operate the shaft 22 to project the rod 27 into the position indicated in Fig. 6. In this projected position of the rod 27 the line 32 connecting it with the catches is taut. Consequently, when the vehicle engages the rod 27 this is swung about into engagement with the roadway, whereby it releases the catches 85 so that the rail sections 15 will assume their elevated position under the tension of the springs 17. This movement of the rail sections raises the chain 30 so that it engages the running gear of the vehicle, between the 90 wheels of the same. As the vehicle advances it naturally carries with it the travelers 31 which run along the rails, thus actuating the chains 40. The operative then applies the brake mechanism to tighten the chains 45 to 95 bring the brake shoes closely into engagement with the chains 40. It will be readily understood that by means of the brake devices the movement of the chains 40 can be strongly resisted and the vehicle thus quickly 100 brought to a stop.

Having thus described my invention, I claim as new, and desire to secure by Letters Patent:—

1. In combination with a roadway, a normally inoperative, movable barrier adapted when projected into an operative position to be engaged by a vehicle traveling along said roadway, and a normally inoperative controlling member for said barrier, said controlling member being adapted to be operated by the vehicle.

2. In combination with a roadway, a normally inoperative, movable barrier adapted when projected into an operative position to be engaged by a vehicle traveling along said roadway, a normally inoperative controlling member for said barrier, said controlling member being adapted to be operated by the vehicle, and means for rendering said last-mentioned member operative.

3. In combination with a roadway, two normally inoperative members adapted to be successively engaged by a vehicle traveling along said roadway, when said members are projected, one of said members controlling the other.

4. In combination with a roadway, two normally inoperative members adapted to be successively engaged by a vehicle travel-

- ing along said roadway, when said members are projected, one of said members controlling the other, said other member constituting a movable barrier, and means for controlling the movement of said barrier. 5
5. In combination with a roadway, a normally inoperative releasing member, means for setting said releasing member whereby it assumes an operative position, a normally 10 inoperative, movable barrier, means for holding said barrier in a normal, inoperative position, and means connecting said releasing member and said last-mentioned means, whereby the engagement of said releasing member by a vehicle releases said barrier. 15
6. In combination with a roadway, a normally inoperative releasing member, means for setting said releasing member whereby it assumes an operative position, a normally 20 inoperative, movable barrier, means for holding said barrier in a normal, inoperative position, means connecting said releasing member and said last-mentioned means, whereby the engagement of said releasing member by a vehicle releases said barrier, and means for controlling the movement of said barrier from a distant point. 25
7. In combination with a roadway, a normally inoperative releasing member, means 30 for setting said releasing member whereby it assumes an operative position, a normally inoperative, movable barrier, means for holding said barrier in a normal, inoperative position, means connecting said releasing member and said last-mentioned means, whereby the engagement with said releasing member of a vehicle releases said barrier, and brake mechanism for controlling the movement of said barrier to bring the vehicle to a stop. 40
8. In combination with a roadway, a normally inoperative releasing member, means for setting said member from a distant point, a normally inoperative barrier member, a traveler connected with said barrier member, a catch for holding said barrier member in an inoperative position, and a connection between said catch and said releasing member, said connection being normally relaxed, and being operative when said releasing member is projected. 45
9. In combination with a roadway, a normally inoperative releasing member, means for setting said member from a distant point, a normally inoperative barrier member, a traveler connected with said barrier member, a catch for holding said barrier member in an inoperative position, a connection between said catch and said releasing member, said connection being normally relaxed, and being operative when said releasing member is projected, brake mechanism for controlling the movement of said traveler, and means for operating said 55 brake mechanism from a distant point. 60
10. In combination with a roadway, a rail, a traveler arranged to move along said rail, brake mechanism for controlling the movement of said traveler, a normally inoperative barrier associated with said traveler, a normally inoperative controlling member for said barrier, and means for setting said controlling member from a distance. 70
11. In combination with a roadway, a rail, a traveler arranged to move along said rail, brake mechanism for controlling the movement of said traveler, a barrier connected with said traveler, means for holding said traveler in a normal position such that said barrier is in a normally inoperative position, a normally inoperative releasing member, means whereby said releasing member can be actuated to release said traveler from its normal position, and means for controlling said releasing member from a distance. 75
12. In combination with a roadway, a rail, a movable rail section having a normal position, a traveler normally positioned upon said rail section, a normally inoperative releasing member, means for controlling said releasing member, a normally inoperative barrier member operatively connected with said traveler, means whereby said releasing member controls said rail section, and means for controlling the movement of said traveler. 80
13. In combination with a roadway, a rail, a movable rail section having a normal position out of alignment with said rail, means tending to move said rail section into alignment with said rail, a traveler normally positioned upon said rail section, a barrier connected with said traveler, a normally inoperative releasing member, means connected with said releasing member for holding said rail section in its normal position, means whereby said releasing member can be set from a distance, and brake mechanism for controlling said traveler from a distance. 85
14. In combination with a roadway, a rail, a movable rail section normally out of alignment with said rail, a spring tending to bring said section into alignment with said rail, a traveler normally positioned upon said rail section, a barrier member connected with said traveler, whereby said barrier is in an inoperative position 90 when said traveler is in its normal position, locking mechanism for holding said rail section in its normal position, a normally inoperative releasing member, a connection between said releasing member and said locking mechanism, whereby said connection is operative when said releasing member is in its projected position, and whereby a further movement of said releasing member releases said locking mechanism, means 95
- 100
- 105
- 110
- 115
- 120
- 125
- 130

for setting said releasing member from a distance, a line connected with said traveler, and brake mechanism operable from a distance and having said line pass through it, 5 whereby said brake mechanism can be operated to control the movement of said traveler.

In testimony whereof I have signed my name to this specification in the presence of two subscribing witnesses.

JOHN PETERSON.
